Herbert Bienen, New York, N. Y.

Application June 18, 1954, Serial No. 31,076

Term of patent 3½ years

(Cl. D87—3)

To all whom it may concern:

Be it known that I, Herbert Bienen, a citizen of the United States of America, residing in New York city, county of New York, and State of New York, have invented a new, original, and ornamental Design for a Handbag or Similar Article, of which the following is a specification, reference being had to the accompanying drawing, forming part thereof, wherein,

I claim:

The ornamental design for a handbag or similar article, substantially as shown.
